UNITED STATES PATENT OFFICE.

FOREST FINLAY, OF PETERSHAM, NEAR SYDNEY, NEW SOUTH WALES, AUSTRALIA,
ASSIGNOR TO OLIVER IMRAY, OF LONDON, ENGLAND.

ROLLER-SKATE.

1,071,721.

Specification of Letters Patent.

Patented Sept. 2, 1913.

Application filed April 25, 1912. Serial No. 693,037.

To all whom it may concern:

Be it known that I, FOREST FINLAY, a subject of the King of Great Britain, residing at No. 10^a Cannon street, Petersham, 5 near Sydney, in the State of New South Wales and Commonwealth of Australia, mechanical engineer, have invented new and useful Improvements in Roller-Skates, of which the following is a specification.

10 This invention relates principally to extensible roller skates in which the frame is constructed with a fore or toe frame and an aft or heel frame each adapted to slide in or upon the other and be clamped in position for the purpose of adjusting the 15 length of the skate to varying lengths of boots and shoes, etc., worn by the users though parts are applicable to inextensible skates.

20 According to this invention the present improvements consist first in constructing the overlapping extensions or shanks of the fore or solepiece and of the aft or heel piece of channel section so that a maximum 25 of rigidity is attained and expeditious and easy adjustment as to length or size of the skate sole is possible secondly in forming the outer of the brackets of the front and rear axle bearing supports of a piece cut 30 from the sole of the skate and bent downwardly and outwardly thirdly in strengthening the toe of the sole and the forward bracket of the front bearing support and at the same time providing a bearing for 35 the adjusting screw of the toe clips by a rib or fin fourthly in strengthening the rear or outer bracket of the back bearing support by a rib or fin and fifthly in forming the inner stay or brackets of the axle bearing 40 supports with flanges or lips to engage the sides of said bearing supports and so firmly hold same.

In order that a practical application of the present improvements may be readily 45 understood the same will be described with reference to the drawings accompanying and forming part of this complete specification in which—

50 Figure 1 is a perspective view of a skate constructed with the present improvements incorporated. Fig. 2 is a sectional elevation on the plane 2—2 Fig. 1 looking rearwardly. Fig. 3 a similar view on the plane 3—3 Fig. 1 looking forwardly. Fig. 55 4 is a longitudinal central sectional eleva-

tion of Fig. 1. Fig. 5 is a sectional elevation on the line 5—5 Fig. 4 looking forwardly. Fig. 6 is a similar view on the line 6—6 Fig. 4 looking rearwardly. Fig. 7 a partial sectional plan on the line 7—7 60 Fig. 4, and Fig. 8 is a bottom plan view from the angle of line 8—8 Fig. 4.

The sole piece 9 has its overlapping part or shank 10 of channel section preferably of arched shape with slot 11 and orifice 12 65 and the heel piece 13 has a similar corresponding shank 14 and this has flanges 16 slot 17 and orifice 18. The stem shank 10 and the shank 14 under or overlap the slot 17 in the latter being positioned above the 70 orifice 12 in the former and a clamping bolt 19 preferably with its head uppermost passes through both and through orifice 20 in the stay bracket 21 which is attached to the front axle bearing supports of known 75 construction and has flanges or lips 22 to engage the sides of said bearing supports.

The slot 11 of the toe piece 9 travels beneath the orifice 18 of the heel piece 13 and a clamping bolt 23 preferably with its head 80 uppermost passes through both and through orifice 24 in the stay bracket 25 which is attached to the back axle bearing supports of known construction and has flanges or lips 26 to engage the sides of 85 said bearing supports.

The front or outer bracket 27 of the front bearing supports is formed of a piece cut and pressed from the sole plate 28 and the toe of said sole plate is supported and 90 strengthened by a rib or fin 29 riveted to or formed on the under side of the sole plate 28 with its rear end 30 abutting and staying said bracket 27 and having a slot 31 forming a bearing for the adjusting screw 32 of the 95 toe clips 33. The rear or outer bracket 34 of the back bearing support is formed of a piece cut and pressed from the heel plate 13 and said bracket is stayed by a rib or fin 35 riveted to or formed on the under side of the 100 said heel plate 13.

In use the skates may be extended and closed by loosening the bolts 19 and 23 drawing the toe and heel pieces apart or pushing them together and are locked at the desired 105 length by tightening said bolts.

The special construction of the overlapping extensions or shanks of the toe and heel pieces though preferred of the arched channel shape as shown may be of any shape such 110

as V channel square channel or tapered flat channel shape in section in which the clamping bolts may pass through both shanks and slide in and upon them so that a maximum 5 rigidity is attained while facilitating and expediting adjustment of the length of skate without removing the clamping bolts the formation of bracket for the axle bearing supports of a piece of the sole plate or heel 10 plate simplifies cheapens and improves the manufacture of the skates the rib or fin under the toe of the sole plate strengthens same and prevents it being bent and cracked and stays the front bracket of the front axle 15 bearing supports and the rib or plate under the heel of the sole stays the rear axle bracket of the back bearing supports.

What I claim, and desire to secure by Letters Patent of the United States, is;—

20 1. In extensible roller skates, in combination, a sole plate provided with a channeled shank portion, said shank portion being provided with a slot and an orifice, and a heel plate provided with a channeled shank portion, said shank portion being provided with an orifice and a slot, said channeled shank 25 portions overlapping one another, one of said channeled portions being slidingly positioned within the other and the orifice in each shank portion registering with the slot 30 in the other shank portion.

2. In roller skates, a foot supporting plate, outer and inner brackets forming an axle

bearing support, said outer bracket being formed out of the material of the plate and 35 bent downward and outward and a downwardly extending rib extending longitudinally with respect to said plate and abutting the bend in said outer bracket.

3. In roller skates, a foot supporting plate 40 and downwardly extending, oppositely disposed outer and inner brackets, an axle bearing support positioned between said brackets, said inner bracket being provided with inwardly extending flanges adapted to engage 45 the sides of said support and hold it against lateral movement.

4. In extensible roller skates, in combination, a sole plate provided with a channeled shank portion, said shank portion being provided with a slot and an orifice, and a heel plate provided with a channeled shank portion, said shank portion being provided with an orifice and a slot, said shank portions overlapping one another, clamping bolts 50 passing through said orifices and slots to hold the plates in adjusted position, and axle bearing supporting brackets secured to said plates by said clamping bolts.

In testimony whereof I have signed my 55 name to this specification in the presence of two subscribing witnesses.

FOREST FINLAY.
